[57] CLAIM

The ornamental design for a combined funnel for a used oil filter and container for gathering residual oil, as shown and described.

DESCRIPTION

FIG. 1 is a perspective view of a combined funnel for a used oil filter and container for gathering residual oil, showing our new design;

FIG. 2 is a front plan view thereof;

FIG. 3 is a side elevational view thereof;

FIG. 4 is a back elevational view thereof;

FIG. 5 is a top elevational view thereof; and,

FIG. 6 is a bottom elevational view.
